CONCEALED HINGE CONSTRUCTION

Frank Hodgson, Marble, Colo.

Application January 3, 1936, Serial No. 57,435

2 Claims. (Cl. 16—178)

The invention relates to hinge mountings and more especially to concealed hinge constructions.

The primary object of the invention is the provision of a hinge, wherein the same is adaptable for the mounting of doors on automobile bodies so that said door can be swung from closed to open position or vice versa irrespective of the curved contour of the body of the automobile and the hinge concealed from view when the door is closed.

Another object of the invention is the provision of a construction of this character, which is comparatively simple in its make-up, thoroughly reliable and efficient in operation, strong, durable, readily and easily placed in working position in a door frame and door, assuring the easy swinging of the door without sagging of the latter and inexpensive to manufacture and install.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a fragmentary vertical sectional view through a doorway of a motor vehicle body showing the door open and supported upon hinges constructed in accordance with the invention.

Figure 2 is a sectional view on the line 2—2 of Figure 1 looking in the direction of the arrows.

Figure 3 is a sectional view on the line 3—3 of Figure 2.

Figure 4 is a sectional view on the line 4—4 of Figure 1.

Figure 5 is a sectional view on the line 5—5 of Figure 4.

Figure 6 is a fragmentary vertical sectional view showing a double hinge arrangement.

Figure 7 is a vertical sectional view through one part of the single hinge.

Figure 7A is a plan view thereof.

Figure 7B is a plan view of another part of the single hinge.

Figure 7C is a sectional view thereof.

Figure 8 is a plan view of another part of the single hinge.

Figure 8A is an edge elevation thereof.

Similar reference characters indicate corresponding parts throughout the several views in the drawings.

Referring to the drawings in detail, A designates generally a portion of the body of a motor vehicle and the same having built therein a

hinged door in superimposed relationship, the upper hinge being provided with a pair of plates 10 which are superimposed one upon the other and are of a shape to match each other while built with these plates are securing flanges 11 accommodating fasteners 12 which stationarily fasten the said plates in matched superimposed relation to each other within the door frame B at the hinge side thereof. These plates at their meeting faces are formed with arcuate guide ways 13 which register with each other and accommodate an arcuate bearing 14 of a swinging part 15 for an attaching ear 16 for the fastening by fasteners 17 of this part to the door C so that said door will be hung by such part 15 and hinged for opening and closing movements. The plates 10 are detachably fastened in superimposed relation to each other by suitable fasteners 18 and the bearing 14 interferes with the guide ways 13 the part 15 on the swinging of the door C can not separate from between the plates 10 and free swinging action of the door C is had.

The lower hinge for the door C includes the pair of plates 19 for the matched arcuate groove or guide way 20 for accommodating the arcuate bearing 21 of the hinge part 22, this arcuate bearing being provided with an arcuate slot 23 accommodating a stop pin 24 as fitted within the plates 19, these plates being mounted in place by the fasteners 25 and are joined with each other by fasteners 26. The part 22 has the attaching ear 27 to which is fastened fasteners 28 for securing it to the door C. The bearing 21 is of a considerable greater arc than the bearing 14 due to the curvature of the door frame B and the door C at the lower portions thereof where the lower hinge is fitted.

In Figure 6 of the drawings there is shown the employment of a double hinge which includes the plates 29 which are provided with the guide ways 30 for the bearings 31 of double swinging parts 32 so as to effect a double hinge arrangement 50 as will appear from Figure 6 of the drawings. Each part 32 is similar to the part 15 hereinbefore described and the plates 29 of each pair are similar to the plates 10.

It will be apparent that the hinge arrangement 55

or mounting effects concealment of the hinges for the door C when the latter is closed.

The stop pin 24 limits the swinging action of the door C when moved to open position and also 5 eliminates the separation of the bearing 21 from between the plates 19 and such bearing freely slides in the guide ways 20 in the said plate.

The plates 10, 19 and 29 are suitably cut away 10 as at 33 to accommodate the parts 15, 22 and 32 when the door C is closed for the close and tight fitting of the said door in the door frame B.

What is claimed is:

1. A hinge of the character described comprising a stationary member formed of a pair of contacting superposed plates having matched arcuate shaped guide ways provided in their meeting 15

faces, an arcuate shaped swinging member slidably fitting in said guide ways, and flanges at the outer sides of said members for fastening of the latter in place on a door frame and door respectively. 5

2. A hinge of the character described comprising a stationary member formed of a pair of superposed plates having matched arcuate shaped guide ways provided in their meeting faces, an arcuate shaped swinging member slidably fitting 10 in said guide ways, flanges at the outer sides of said members for fastening of the latter in place on a door frame and door respectively and means separably joining the plates together in contacting superimposed relation to each other. 15

FRANK HODGSON.
